UNITED STATES PATENT OFFICE

WILLIAM H. WILKINSON, OF BROOKLYN, ASSIGNOR TO THE J. L. MOTT
IRON WORKS, OF NEW YORK, N. Y.

DESIGN FOR A FIRE-PLACE.

SPECIFICATION forming part of Design No. 15,153, dated July 15, 1884.

Application filed May 15, 1884. Term of patent 7 years.

To all whom it may concern:

Be it known that I, WILLIAM H. WILKINSON, of Brooklyn, in the county of Kings and State of New York, have invented and produced a new Design for Fire-Places, of which the following is a specification, reference being had to the accompanying photograph, forming part thereof.

The lintel of the fire-place is ornamented with the molded edge *a*, the projecting animals' heads *b*, with circles in relief, and the leaflet and acorn ornaments at *d*, and the base-molding *c*.

The fire-place jambs terminate at the upper parts with ornamental leaflet bracket-pieces *e*, and below these are leaflet and acorn ornaments *d*, similar to those upon the lintel. The surfaces of the fire-place back and jambs are ornamented with raised ribs crossing each other, and forming square and oblong panels containing leaflet ornaments, as at *i*, and in the larger squares there are bird ornaments *g* upon branches in relief.

The urn ornaments at *k* do not form any part of this design, they being part of the and-irons.

The fender-piece is provided with a central animal's-head ornament, *b*, and leaflet and acorn ornaments *d*, similar to those on the lintel, and there are the urn ornaments at *m* and the scroll end pieces, *n*, as represented.

I claim as my design—

1. The design of the head *b* and leaflet and acorn ornaments *d* in relief, substantially as shown.

2. The design of the lintel, composed of the heads *b*, leaflet and acorn ornaments *d*, and the molded edges *a*, *c*, and the circles around the heads, substantially as shown.

3. The design of the ribs crossing each other with leaflet ornaments and the birds upon branches in relief, substantially as shown.

4. The design of the fender-piece, composed of the head *b*, leaflet and acorn ornaments *d* in relief, the urns *m*, and the scroll end pieces, *n*, substantially as shown.

Signed by me this 9th day of May, A. D. 1884.

W. H. WILKINSON.
